Fig. 3.

Invention
Fred Green:

By Chas. Gillman
Attest.

UNITED STATES PATENT OFFICE.

FRED GREEN, OF CHICAGO, ILLINOIS.

GAUGE OR TOOL.

Application filed February 6, 1925. Serial No. 7,362.

To all whom it may concern:

Be it known that I, FRED GREEN, a subject of the King of Sweden, residing at Chicago, in the county of Cook and State of Illinois, have invented certain new and useful Improvements in a Gauge or Tool, of which the following is a specification.

This invention relates, generally, to improvements in tools or instruments for use in the building of structures made principally of concrete, with surfaces thereof finished with a covering of cement or other plastic material, but has particular relation to a device which is especially intended for use in the construction of stairs of plastic material, such as concrete and cement, and it consists in certain peculiarities of the construction, novel arrangement and combination of the various parts thereof as will be hereinafter more fully set forth and specifically claimed.

As is well known, in the above mentioned type of stairs, it is necessary, or at least desirable, in order that the steps thereof may be self-draining, or to prevent the accumulation of water thereon, and the same freezing, said steps shall be inclined from the risers of the stairs, and for the sake of attractiveness and symmetry, the inclinations thereof should be uniform, and besides, the slant or inclination to the upper surfaces of the steps must be quickly given while the material thereof is in a plastic state.

The principal object of the invention is to provide a gauge or tool which shall be simple and inexpensive in construction, strong, and durable, with its parts so made, arranged, and co-operating with one another as to furnish not only means for readily giving slant or inclination to the upper surfaces of steps, but also for quickly smoothing the same.

Another object of the invention is the provision of a gauge or tool of the above mentioned general character whereby the desired degree of inclination or slant of the upper surface of steps of a stairway can be attained with perfect accuracy and uniformity. Still another object is to provide a gauge or tool which can be folded into compact form and locked in such condition, thus enabling it to be readily carried.

Other objects and advantages of the invention will be disclosed in the following description and explanation.

In the accompanying drawing, which serves to illustrate an embodiment of the invention,—

Fig. 1 is a perspective view of a portion 60 of a stairway showing a gauge or tool in place thereon with its parts arranged for giving a desired slant to the covering or upper surface of one of the steps thereof.

Fig. 2 is a side view showing the device 65 in its folded position, and

Fig. 3 is a slightly enlarged bottom plan view of a portion of the device as shown in Fig. 2.

Like numerals of reference refer to corresponding parts throughout the different views of the drawing.

Referring now more particularly to Fig. 1 of the drawing, the reference numeral 5 designates as a whole a portion of the stairway of the concrete and cement type, which stairway may be built in the usual or ordinary way, that is, by employment of concrete 6 roughly fashioned into steps, which concrete steps may be supported in the usual or any well known way, and each of which is covered with a layer or coating of cement 7 or similar plastic material for the purpose of giving a smooth finish thereto.

The gauge or tool consists of a base bar 8 which is made of channel iron and has its channel presented upwardly as is clearly shown in Fig. 1 of the drawing. The outer end of the bar 8 is provided with a pair of spaced extensions 9 which are slightly upturned as shown in Fig. 2, and have located therebetween one end of a lever bar 10 which is secured to the bar 8 by means of a pivot 11. The bar 10 is also of the channel type with its channel presented downwardly and said bar is of such width as to fit within the channel of the base bar 8 when the parts are folded together as shown in Fig. 2 of the drawing.

The bar 10 is provided at its free end with a longitudinally disposed extension 12 which not only affords a handle for the movement of the bar 10 but also provides a rest for the device which may sometimes be employed.

Pivots secured at its lower end between the walls of the bar 8 at the end thereof

opposite the pivot 11 is an arm 13 which is provided with a graduated scale indicating any desired dimensions. This arm is extended through a suitable opening 14 in 5 the lever bar 10 at the juncture of said bar with its extension 12 and the last named bar may be held in fixed position with respect to the arm 13 by means of a thumb screw 15 seated in one side of the bar 10 10 in such a way that its inner end will contact with the arm 13.

As is clearly shown in Figs. 1 and 2 of the drawing, the ends of the walls of the channel bar 8 adjacent the arm 13 are bent inwardly towards each other yet do not contact with one another, which arrangement will permit the said inwardly bent portions of the walls of the channel bar 8 to be received by the recesses 16 with which each 20 of the walls of the channel in the bar 10 is provided near the arm 13 when the parts are in their positions shown in Fig. 1 of the drawing, and thus enable the bars 8 and 10 to be folded together. The bar 10 has 25 mounted thereon and depending therefrom a thumb screw 17 the head of which is adapted to engage the pivoted end of the arm 13 when the latter is turned to its folded position as shown by dotted lines in Fig. 30 2 and by continuous lines in Fig. 3, thus locking the bars together.

As is clearly shown in the different views of the drawings, the walls of the channel in the bar 10 terminate at their ends adjacent the opening 14 in said bar, and each provides a shoulder 18 to rest against the face of one of the risers 19 with which the stairway is equipped in the construction thereof, in such a way that the extension 12 40 or handle of the bar 10 may rest on the upper edge of said riser as is clearly shown in Fig. 1 of the drawing.

From the foregoing, and by reference to the drawing, it will be readily understood 45 and clearly seen that after the finishing coat or covering 7 of plastic material has been placed on a step of the concrete material 6 and the risers 9 have been positioned as shown in Fig. 1 of the drawing, the desired 50 inclination or slant to be given the finishing material 7 may be attained by the use of my instrument or device in the following manner: The base bar 8 carrying the lever bar 10 and arm 13 assembled about as shown in 55 Fig. 1, can be placed near or at one end of the step with one end of said base bar resting against or near the lower portion of the face of the upper riser and with the other end of said bar overhanging the lower 60 riser. Now, assuming that the parts have been adjusted with respect to one another to give the desired inclination to the upper surface of the step and that the lever bar 10 is held in fixed position with respect to the 65 arm 13 by the set screw 15, it is mani-

fest that the shoulders 18 near the extension 12 of the lever bar will rest against the upper portion of the face of the upper riser, thus acting as a guide, when it is manifest that by sliding the base bar 8 towards the 70 opposite end of the step from its position shown in Fig. 1, the plastic finish cement or material will be rendered smooth and any excess of such material scraped off in the movement of the base bar 8 of the device. 75

To prevent the plastic material entering the upwardly presented channel of the base bar 8, a block or piece 20 of wood or any suitable material and the requisite size, may be placed in said channel so as to extend a considerable distance upwardly from the base bar as is illustrated in Fig. 1 of the drawing. The handle 12 of the lever bar will ordinarily rest on top of the upper edge of the upper riser as shown, but it is manifest that the shoulders or rests 18 may depend a considerable distance below the said handle so as to permit the latter to occupy a position above and out of contact with the said edge of the said riser. By moving 80 the free end or portion of the lever bar downwardly on the arm 13, it is manifest that the inclination of the base bar will be increased and by moving it upwardly, said 85 inclination will be diminished. 90

Having thus fully described my invention, what I claim as new and desire to secure by Letters Patent is:

1. In a device of the class described, the combination with a base bar, of a lever bar 100 pivotally mounted at one of its ends on one end of said base bar and having near its other end an opening, an arm movably extended through said opening and pivotally secured to said base bar near its other end, 105 and co-operating means on said arm and the lever bar for holding them in fixed relation to one another.

2. In a device of the class described, the combination with a channeled base bar, of a channeled lever bar pivotally connected at one of its ends to one end of said base bar with its channel presented towards the latter, said lever bar having near its free end a shoulder or stop member and near the same 110 an opening, an arm pivotally secured to said base bar near its other end and movably extended through said opening, and a set screw intersecting said opening and carried by said lever bar. 115

3. In a device of the class described, the combination with a channeled base bar having at one of its ends the walls of said channel inclined towards each other, said bar presenting its channel upwardly, of a channelled lever bar pivotally connected at one of its ends to the base bar near its end opposite the said inclined wall portions and presenting its channel toward the base bar, 125 said lever bar having at its free end a han- 130

dle or extension and provided with a depending shoulder or stop member and near said stop member an opening, an arm pivotally secured to said base bar between the 5 inclined portions of the walls of its channel and movably extended through said opening in the lever bar, co-operating means on said arm and the lever bar for holding them in fixed relation to one another, and a set screw mounted on and depending from the lever bar at a point near the pivoted end of said arm when the parts are folded together.

FRED GREEN.
